UNITED STATES PATENT OFFICE

ANDREW KIMMINS, OF DETROIT, MICHIGAN

DESIGN FOR A GAME BOARD

Application filed November 28, 1930. Serial No. 37,808. Term of patent 7 years.

To all whom it may concern:

Be it known that I, ANDREW KIMMINS, a citizen of the United States, residing at Detroit, county of Wayne, and State of Michigan, have invented a new, original, and ornamental Design for Game Boards, of which the following is a specification, reference being had to the accompanying drawing, forming a part thereof.

I claim:

The ornamental design for a game board as shown.

ANDREW KIMMINS.
